UNITED STATES PATENT OFFICE

HORACE W. ASH, OF SOMERVILLE, MASSACHUSETTS, ASSIGNOR TO WARREN BROTHERS COMPANY, OF CHARLESTON, WEST VIRGINIA, A CORPORATION OF WEST VIRGINIA.

HEATER AND DRIER.

No. 887,906.

Specification of Letters Patent.

Patented May 19, 1908.

Application filed June 10, 1905. Serial No. 264,703.

To all whom it may concern:

Be it known that I, HORACE W. ASH, of Somerville, in the county of Middlesex and State of Massachusetts, a citizen of the 5 United States, have invented a new and useful Improvement in Heaters and Driers, of which the following is a full, clear, and exact description, reference being had to the accompanying drawings, forming a part of this 10 specification, in explaining its nature.

My invention relates especially to a portable heating and drying device for heating and drying small stone, gravel, sand, and other material.

15 In the manufacture of certain kinds of pavements it is necessary to dry and to heat some of the materials or ingredients used in their composition, and it is desirable that such drying and heating should be carried on 20 as near the place of final use as possible. As this place of use is constantly changing, it is necessary that the drying and heating device be easily portable. It is necessary for this kind of work, also, that the said device be 25 simple of structure, of relatively large capacity, and of sufficient strength to withstand the hard usage to which it is necessarily subjected. It is also desirable that the device be easily repaired and by parts 30 which are in common use and easily obtained and so that the device may be repaired on the spot or without removal to a repair shop. Heretofore the devices commonly used for 35 this purpose have been unsatisfactory for many reasons, which it may not be necessary to state here.

In order that strength may be secured I have employed a structure largely composed of angle iron and sheet iron combined as will 40 be hereinafter specified.

To secure a quick, continuous and uniform heating of the ingredients I have used a form of structure which permits the ingredients to be fed in at the top, delivered at the 45 bottom, and in their movement from the top to the bottom to be brought into contact with heating surfaces disposed to cause the material to be brought into contact with them as it falls.

50 To permit of the immediate renewal of parts, I have caused such portions of the device as are likely to need renewal, viz,—the fire brick and the heating tubes, to be made of such brick and of such tubes as are in

common use and have also caused them to be 55 secured to their supports in the device in such a manner as to be easily and quickly removed and replaced. I have also so devised the structure that the dried and heated material may readily be removed from either 60 side of it and that pending removal it may be held therein without liability of waste by escape.

I will now describe the invention in detail in conjunction with the drawings forming a 65 part of this specification where—

Figure 1 is a longitudinal section. Fig. 2 is a cross section, and Fig. 3 is a front elevation.

In order that the drying and heating de- 70 vice may be portable it is mounted upon two axles A, A¹ of which the forward A is some-what lower than the rear one A¹. The axles are located preferably as far apart as possible in order to provide access to the drier from 75 its sides.

The drier comprises two parts, viz.,—the furnace B and the drying chamber C. The furnace is at the back or rear of the drying chamber and from it there extends through 80 the drying chamber to a flue D in front of the drying chamber the lines of tubes E, E¹ and E². From the flue D there extends to the flue D¹ over the furnace and at the rear of the drying chamber the lines of tubes E³ and E⁴. 85 The products of combustion thus pass forward from the furnace B through the pas- sages in the tubes E, E¹ and E² to the flue D, thence upward in said flue and thence back- 90ward through the passages in the tubes E³, E⁴ to the flue D¹ from whence they escape to the atmosphere through an opening at the top of the flue.

The lines of tubes are arranged with respect 95 to each other as represented in Fig. 2 and so that the tubes of every two lines occupy a staggered relation, the tubes of every other line preferably being in the same vertical planes. The number of tubes in the two lower lines preferably is smaller than the 100 number in the third line in order that there may be introduced into the drying chamber near its bottom side walls c, c¹ which are in- clined from the vertical side walls c², c³ in- 105 ward. The lower ends of these inclined walls end at a suitable distance above the bottom c⁴ of the chamber and they are separated from each other sufficiently to form an out-

let c^5 to the bottom c^4 , and their inclined surfaces cause the material passing through the chamber adjacent to the sides to move in towards its center and said outlet, and compel the material to pass uniformly down through the tubes in the heating chamber. The material is removed through the bottom through long rectangular openings c^6 and c^7 , one on each side, and to provide a shovel support and also a grate for preventing the escape of the material from the bottom, the bottom is provided with the upwardly inclined extensions c^8 , c^9 which project beyond the line of the sides c^2 , c^3 any desired extent, (see Figs. 2 and 3.)

The material to be dried and heated is fed in any desired way into the top of the chamber which is open. The chamber is usually kept filled with the material. As it is removed from the bottom the material gradually moves downward and in its course is brought into contact with the heated surfaces of some of the tubes, the material being caused by the arrangement of the tubes, by their sides and by their spacing to be divided or separated into narrow, thin bodies having continuity only for the height of the passages between one set of tubes, the bodies being continuously broken by each succeeding line of tubes and so that material which may be at the center of some of the passages between the tubes is caused to be brought into contact with the surfaces of other of the tubes in its descent. The arrangement and sides of the tubes also is such that the material passing through the chamber has no tendency to run from the one side of it to another, but on the contrary a direct, vertical descent of all the material takes place uniformly in line with that portion which is being removed from the bottom of the shovel.

The rate of movement of the material through the drier depends, of course, upon the rapidity with which it is discharged from the bottom, and there is thus provided a means whereby the time used in heating may be easily regulated and the degree of heat employed may be controlled and variations in the degree of heat and in the degree of heating of the material may be easily secured. Not only this, but the device also provides means for keeping the material in a uniformly dry and heated condition until the time of its use and without requiring that it be in any way treated or handled.

The drier being rectangular in shape and mounted as I have described and provided with discharge outlets at each side permits it to be supplied with material from either or both sides and to deliver its material at either or both sides.

The furnace B has a fire door b and any desired form of grate bars b^1 . The grate bars are arranged sufficiently below the openings in the lowest line of tubes E^2 to prevent fuel

from entering them, and the combustion chamber b^3 in the upper part of the furnace is of sufficient height to permit the products of combustion to readily enter the passages of the three lines E , E^1 , E^2 of tubes.

The flue D^4 is shown as an extension of the combustion chamber, but is separated from it by a partition of fire bricks d , which rest upon the flanges d^1 and are easily removable therefrom.

The furnace, heating chamber and flues are made of angle iron and plates which are combined to secure great strength of construction, but are relatively light in weight. The construction is also such as to permit the use of common fire brick in the furnace, its ready placement and removal, and of common cast iron soil pipe as the heating tubes of the drier and their ready placement and removal.

The sides b^2 and the rear end b^3 of the furnace are made of sheet metal plates riveted at their edges to angle iron and the sides, ends and top of the flue D are similarly constructed, the top plate having the escape openings from the flue D^1 before referred to.

The side plates and rear plate of the furnace are lined upon their inner surfaces with common fire brick of ordinary rectangular form and these bricks are supported upon flanges of angle iron along the lower edge of the plates and are attached to the side plates and to the rear plate by means of bolts with cast iron washers to bear against the bricks and which pass through the bricks at their corners and through holes in the plates and receive fastening nuts upon the outer surfaces of the plates. The bolts preferably are placed at the meeting points or corners of four bricks and this permits one bolt to act to partially attach four bricks to a plate. It is not necessary that a bolt be located at each of the four corners as every other one will answer, especially when alternated as represented in the drawings. By this construction any type of brick which will answer for a lining and which is rectangular in form may be used, either originally or for repairs and any burned out bricks may be readily removed and new ones substituted by simply detaching one or more of the bolts and without removing the entire lining and without requiring special types of lining.

The top of the furnace is formed of rectangular fire bricks b^4 which are supported on the flanges b^5 of angle iron, extending across the furnace top from side to side, the brick being cemented in place by fire clay or cement. They are uncovered and are thus in an accessible position for placement and renewal. It is not necessary to indicate specifically the position of each of the angle irons and metal plates of the structure, it being sufficient to say that the angle irons are placed at the edges and corners wherever it

is necessary to reinforce or strengthen the structure and that the plates are riveted to these angle irons.

The tubes preferably are of common cast iron soil pipe having at one end a ball-shaped enlargement e around which is a collar or bead e^1 adjacent to the opening of the tube and having at the other end the cylindrical enlargement e^2 . This is the ordinary structure of this type of pipe, and the drier is made of a sufficient length to receive the commercial length of such pipe. In order that they may be easily placed or inserted and detached I have arranged at each end 10 of the drying chamber the plates F and F¹. The sectional plate F forms the partition between the furnace, combustion chamber and flue D¹ and the drying chamber and receiving space beneath it. The plate F¹ forms the partition between the drying chamber and the front flue D and also the front end of the receiving chamber. The sectional plate F is made to receive the beads or collars e^1 of the tubes and also to support 20 these ends of the tubes, the plate having a collar f for each tube provided with inward extending flanges f^1, f^2 , the first of which closes behind the bead e^1 and the second in front of it, and each collar thus serves to support the end of a pipe and also to prevent 30 it from being dislodged by endwise movement. The sections of the plate are of such shape that the division between them extends horizontally through each line of tubes 35 holding collars. In the structure shown there are five lines of tubes and the sectional plate is made in six sections, each of which sections is independently bolted by the bolts f^3 to flanges of angle iron located to receive them.

It will be understood that the lowermost section of the sectional plates operates as a support for the rear ends of the lowest line of tubes; that the next plate in order operates with the first to hold the ends in place and also acts as a support for the rear end of the second line of tubes, and that the third, fourth and fifth sections of the plate have similar functions in conjunction with the second, third and fourth lines of tubes, while the upper section serves to coöperate with the fifth section to hold the upper line of tubes.

The sectional plate F forms the front wall 55 of the furnace and combustion chamber and it preferably is made of cast iron and because of its sectional shape, portions thereof which are burned out may be removed and others substituted without requiring the loss of the entire plate. It will be understood that the sections of the plate so join along their edges as to provide for a continuous wall to the furnace and combustion chamber between them and the drying chamber and between 60 the flue D¹ and the drying chamber.

The front F¹ of the drying chamber may be made of independent sections, but I prefer to make it of sheet iron as it will not be so much affected by the heat as will the rear sectional plates. In holes in this plate the front ends of the tubes are supported. This plate is not provided with collars as is the plate F and the ends of the tubes supported by this plate are free to move crosswise if as the tubes are longitudinally expanded by variations in temperature.

The rear axle A¹ is attached to the rear lower corner of the furnace box by means of straps g surrounding the axle and riveted to the end and bottom of the furnace box. The axle is also bolted or riveted to the straps. The forward axle A supports a king-pin a^1 and the section a^2 of the fifth wheel. The section a^3 of the fifth wheel, mounted upon the section a^2 is riveted or bolted to the arms a^4 which are riveted to angle irons forming a part of the frame of the machine. These arms are bent as represented and the king-pin passes through holes in the sections of the fifth wheel and also through a block a^5 on the upper section. A collar a^6 fast to the king-pin is contained in a recess a^7 between the two sections of the fifth wheel.

The advantages of the construction and the operation of the device have been described in conjunction with the description of the objects of the invention and its construction.

It will be understood, of course, that usually a soft coal is employed in the furnace, but whatever fuel is used the products of combustion pass forward from the furnace through the lower set of tubes into the forward flue, then upward in the flue and backward to the passages of the upper sets of tubes to the rear flue D¹ from which they escape into the atmosphere. This provides the drier with a relatively large number of rows of heating tubes passing through it from end to end, arranged to operate as above described and which form a large number of independent heating surfaces for the purposes specified with which the material to be dried and heated is brought into contact as it moves downward through the chamber.

A structure of this kind is especially well adapted for use in drying and heating material for the manufacture of pavements and also to resist the hard usage to which such devices are put.

Having thus fully described my invention, I claim and desire to secure by Letters Patent of the United States:—

1. In a drier and heater for drying and heating pavement and other material, a receptacle having an opening through which the material is fed to it, an outlet at its bottom through which said material is discharged, a furnace located at one end of said receptacle, flues extending from said furnace 125

through said receptacle whereby the contents of said receptacle are dried, a plate or platform for said receptacle below said flues and said outlet, and openings to withdraw 5 the dried materials from said platform.

2. In a drier and heater for drying and heating pavement and other material, a receptacle having an opening through which material is fed to it, an outlet at its bottom 10 through which it is discharged, a number of lines of heating tubes extending across the receptacle from end to end and with which tubes the material comes into contact as it moves from the top to the bottom of the receptacle, a platform below the outlet for receiving and holding the material as it leaves 15 the outlet, and shelves extending from said platform outward on each side of the receptacle and a furnace at one end of said receptacle whereby it will not interfere with the downward passage of the material through 20 said receptacle.

3. In a drier and heater for drying and heating pavement and other material, a receptacle through which the material is fed having its sides inclined inward to a discharge outlet, a platform located below said discharge outlet and shelves upwardly inclined extending from said platform on each 30 side.

4. In a drier and heater for drying and heating pavement and other material, a receptacle having an opening through which the material is fed to it, an outlet at its bottom 35 through which it is discharged, a number of lines of heating tubes extending across the receptacle from end to end, arranged to form vertical serpentine passages, and with which

tubes the material comes into contact as it moves from the top to the bottom of the receptacle, a platform below the outlet, shelves extending from the platform on each side, a furnace at the rear of the receptacle having a combustion chamber connecting with a number of tubes, a flue at the forward end of the receptacle connecting the passages in the tubes extending from the combustion chamber with the passages in the tubes extending from said flue to a rear flue, an axle attached to the rear of the furnace, and another axle 40 attached to the forward end of the receptacle 45 having a pivoted relation thereto.

5. A portable drier and heater for drying and heating pavement and other material comprising a receptacle and a furnace 50 formed of metal plates and angle iron frames and disposed with respect to each other to provide a receptacle having an opening at its top through which material is fed to it and an outlet narrower than the opening at its bottom through which it is discharged, a flue at the forward end of said receptacle, a furnace, combustion chamber and flue at the rear of said receptacle, tubes connecting the combustion chamber and flue above it with the 55 forward flue, which tubes extend across the receptacle from end to end, a platform below the discharge outlet of the receptacle, shelves extending from each end thereof and axles upon which the said drier and heater 60 is mounted.

HORACE W. ASH.

In presence of—

ROBERT E. BREWER,
MARTIN V. FOLEY.
